UNITED STATES PATENT OFFICE

FRANK B. STIRCKLER, OF REVERE, MASSACHUSETTS, ASSIGNOR TO JOHN W. MACKINTOSH, OF SHARON, MASSACHUSETTS.

LACING-TIP.

No. 818,946.

Specification of Letters Patent.

Patented May 8, 1906.

Application filed November 7, 1904. Serial No. 231,707.

To all whom it may concern:

Be it known that I, FRANK B. STIRCKLER, a citizen of the United States, and a resident of Revere, in the county of Suffolk and State of Massachusetts, have invented an Improvement in Lacing-Tips, of which the following description, in connection with the accompanying drawings, is a specification, like letters on the drawings representing like parts.

The invention to be hereinafter described relates to tips for shoe-lacings, and more particularly to such tips as are molded or compressed upon the end of the lacing. In accordance with my invention this lacing has at its ends a hard or molded tip partially enveloping and concealing the fibrous material of which the lacing is made. This form of lacing-tip consists of celluloid or other similar moldable material having its ends tapered, one tapered end serving as a threading-point by which the lacing may be led through an eyelet, while the other is contracted to form an anchor or locking means for holding the tip securely in place upon the lacing.

In order to enable those skilled in the art to which my invention relates to more readily make and use the same, I will describe my invention in connection with the drawings forming part of my application.

Figure 1 shows one end of a lacing having a tip embodying my invention, the tip being shown in section. Fig. 2 shows in side elevation a lacing with a finished tip. Fig. 3 shows a lacing having a tube of the material from which my tip is molded applied to it before the tube has been compressed to form tips. Fig. 4 is a side elevation, on a greatly-enlarged scale, showing the split portion of my improved celluloid tip.

The tip t , as clearly shown in Fig. 1, is approximately elliptical in longitudinal cross-section. I preferably make this tip of celluloid or some similar moldable material in order to more easily impart to it the desired shape and proportions. In order to securely attach the tip t to the lacing d , the inner end of the said tip is considerably contracted, as at d^2 . The threading end of the tip is conoidal in shape, as indicated at p . Since the greater part of the wear and tear necessarily falls upon the threading end of the tip t , I have strengthened this end, as clearly shown at p , by increasing the thickness of the material thereof. In order to maintain the strength of the tip and at the same time to insure its resiliency, that it may successfully withstand compression in a longitudinal direction, I have provided the said tip with kerfs or splits, as is clearly shown in Fig. 4 at d' . By this construction a thoroughly-resilient and at the same time perfectly-durable lacing tip is produced.

Having thus described my invention, what I claim, and desire to secure by Letters Patent of the United States of America, is—

1. In an article as described, a lacing-tip, comprising a body portion having a conoidal threading end and kerfs or splits in said body portion.
2. In an article as described, a lacing-tip, comprising a body portion having a thickened conoidal threading end and kerfs or splits in said body portion.
3. In an article as described, a lacing-tip, comprising a body portion having a conoidal threading end, and kerfs or splits in said body portion, said kerfs or splits running longitudinally of said body portion.

In testimony whereof I have signed my name to this specification in the presence of two subscribing witnesses.

FRANK B. STIRCKLER.
